UNITED STATES PATENT OFFICE.

THOMAS B. SLATE, OF WASHINGTON, DISTRICT OF COLUMBIA, ASSIGNOR TO AMERICAN MECHANICAL IMPROVEMENT COMPANY, OF WASHINGTON, DISTRICT OF COLUMBIA.

AIR-PROPELLER.

1,238,838.

Specification of Letters Patent.

Patented Sept. 4, 1917.

Application filed November 25, 1916. Serial No. 133,367.

To all whom it may concern:

Be it known that I, THOMAS B. SLATE, a citizen of the United States, residing at Washington, in the District of Columbia, have invented new and useful Improvements 5 in Air-Propellers, of which the following is a specification.

My object is to improve the construction of air propellers in order to remedy the in- 10 efficiency experienced in the present type of solid or non-adjustable air propeller blades. I have devised a novel adjustable governor-controlled air propeller blade for the purpose of adjusting the pitch of the blades 15 according to the load the propeller is subjected to under the various conditions experienced by an aeroplane, or any other use the air propeller is commonly put to, owing to the fact that an aeroplane has 20 to traverse steep grades in rising to considerable heights and likewise in descending. Or if the propeller is being used on an aerosled, hydroaeroplane, hydroplane, or any other vehicle driven by an air 25 propeller it likewise has to climb or descend grades, subjecting the power plant and propeller to varied loads. For example, if a propeller blade was set at a four foot pitch, by which I mean that the machine if free to 30 move without friction would travel four feet per revolution of propeller, and the propeller was of the proper size to consume the full load of the engine at its maximum speed, (revolutions per minute,) and the 35 power of the engine was sufficient to drive the machine at a proper or desired speed on level ground, or at a level while passing through the air as an aeroplane, and if the machine were brought into an elevating position, or had to climb a hill if traversing 40 the ground, the pitch of the usual propeller blades would be far too great to make the climb. It would be necessary therefore with the usual type of propeller blades to carry 45 several times the necessary power to drive the machine at a desired speed on a level in order to be able to climb grades or ascend at a desired rapidity if being used on an aeroplane, making it impossible to use the 50 power of the engine with a high degree of efficiency on even or descending grades.

It is my object to provide a novel governor-controlled propeller in which the speed of the engine and the propeller shaft 55 (revolutions per minute) will increase or

decrease automatically the pitch of the propeller blades with the varying power requirements. This operation also automatically controls the speed of the engine to whatever amount the propeller is set for by 60 the adjustment of the spring in the governors. This also automatically adjusts the pulling power or thrust of the propeller according to the speed traveled (miles per hour) and the amount of power supplied by 65 the engine, so as to give the greatest efficiency from the amount of power supplied at all times, regardless of the grades climbed or descended. It also prevents any noticeable change in the speed of the engine, (revolutions per minute,) in case of sudden changes in grade conditions, or in case of accident or error in the control of an aeroplane while in the air. The change 70 in load conditions if suddenly changing 75 from upgrade to downgrade, whether in the air or on the ground would affect the speed of the engine by releasing the load it is subject to, allowing the engine to suddenly change to a high rate of speed, (revolutions 80 per minute,) setting up gyroscopic force in the propeller, propeller shaft, and crank shaft of the engine, said force being sufficient in various instances to break the shaft, propeller, or possibly wreck the machine. 85 My invention positively prevents this overspeed, regardless of the amount of change of load conditions, as a few revolutions per minute over the speed the governors are set for will turn the propeller blades to right 90 angles with the direction of the rotation of the blade or as nearly so as the speed attained would require, and by this performance hold the engine within a few revolutions per minute of a predetermined speed. 95

I attain these objects by the mechanism illustrated in the accompanying drawings, in which—

Figure 1 is a side elevation of the invention, longitudinal with the propeller blades; 100 and Fig. 2 is a side elevation at right angles with Fig. 1—one propeller blade being removed—showing part of hub pieces 2 cut away.

Similar numerals refer to similar parts 105 throughout the several views.

Referring to the accompanying drawings, I provide a propeller shaft 1, to which is mounted a propeller hub 2. Adjustably mounted to hub 2 is a propeller blade 3. I 11

provide a governor arm band 4 clasped to propeller blade 3, as shown in Fig. 1, and having a geared portion 15. Mounted to governor band 4 by its threaded end, member 4 having a corresponding threaded portion, is a governor arm 5. On the outer end of arm 5 is a suitable governor weight 6. And extending between the pair of governor arms 5 near their outer or weighted ends I provide a suitable governor spring 7, as shown in Fig. 1. A bracket 8 is provided to carry the end of propeller blade. Attached to mounting 14 in the center of propeller blade is a bracket 9, as shown in Fig. 1. A bolt 10 is provided and extends through mounting 14 in center of propeller blade. I provide a bolt 11 in end of propeller blade through hub mounting 8. 12 designates bolts through hub pieces 2, and 13 designates the end of propeller blade 3. 14 is a bracket in center of propeller blade 3, through which bolt 10 passes.

My invention operates as follows: The propeller blades 3 are movably mounted to brackets 9, 8 and 9, having their axes almost at right angles with propeller shaft 1, but offset in the center where they intersect each other by means of the geared bands, to permit of the provision of gear elements 15, as illustrated. The object is to cause both blades to operate simultaneously and to cause each one to move exactly the same on its axis as the other, in order to exactly balance the load on both blades at all degrees of their pitch. When the propeller shaft and propeller are revolved at a high rate of speed, the centrifugal force of governor weights 6, revolving around the axis of propeller shaft 1, tends to stretch spring 7, causing the propeller blades to turn on their axes, shown at 10 and 11, the gear teeth 15 operating to cause both blades to turn to the same extent, whether the speed is increasing or decreasing. The object of this particular type of governor is to simplify construction, reducing the number of working parts to a minimum, and making positive its operation, as positiveness is very essential in this class of machines. The governor arms 5, governor weights 6, governor bands 4, and propeller blades 3 are fastened together in a manner to operate as one piece, having only two bearings for each blade, as shown by bolts 10 and 11. The only other place for wear or lost motion is in gear teeth 15, which carry no load of operation any more than merely causing the two propeller blades to revolve on their axes evenly or in the same proportions. The governor arm 5 is preferably threaded at the end connected to governor band 4, it being adjustably connected with band 4 by a correspondingly threaded portion of that member, thereby clamping band 4 onto the circular end or shank of propeller blade 3.

The governor arm 5 takes the place of a clamp bolt for clamping band 4 to propeller blade. Band 4 being adjustable on propeller blade, by unscrewing governor arm 5 the propeller blade can be set in proper position as regards the pitch of the blade at any predetermined position of the governor weights.

An important improvement is attained by controlling the pitch of the blade and keeping the pressure all on one side of the blade. A thin metal blade is made possible and such a blade cuts through the air without disturbing it, leaving it in solid formation and thereby giving the propeller a foundation on which it is possible to transmit the power from the engine to thrust on the propeller shaft. The air being in solid formation after the propeller blade has passed through it and pushed it back from the blade, leaves an undisturbed substance or body of air on the back or rear side of the propeller blade. When a thick blade is employed or a blade that would create resistance as it passed through the air in its course of rotation, it causes the air to whirl and twist with the blade. This leaves a disturbed body of air back of the blades and causes the pressure created from the force of each of the blades to break into the disturbed air of the last revolution of the blades, thereby greatly reducing the solidity of air back of the blade. This causes the blade when on the usual construction to depend on the vacuum created in front of the blade by the air pushed back. Experiments conducted with the invention have demonstrated that this propeller attains the new result above described.

When traveling through air at the rate of 350 miles an hour the largest circumference or the extreme ends of the propeller blades are afforded the resistance described as the air becomes at this high rate of speed a substance more solid than water so far as resistance is concerned. The use of a thin metal propeller blade as employed in my invention makes possible the transmission of more power exerted, to the propeller in thrust longitudinal with the propeller shaft instead of consuming a large per cent. of the power in rotative resistance as occurs with the usual type of propeller.

What I claim is:

1. An air propeller comprising a governor controlling the pitch of its blades which includes the meshing geared bands mounted upon the blades, whereby the blades are caused to move in unison under the action of the governor.
2. A governor-controlled propeller comprising governor-controlled blades offset at right angles to the propeller shaft and mounted to operate in opposite directions to each other for changing the pitch of the

blades while in motion, and having no other movable parts than the propeller blades, the governor mechanism being directly connected to the blades and operating as a part thereof.

3. In a governor-controlled air propeller, the combination of a propeller shaft, a propeller hub mounted to the shaft, propeller blades movably connected to the propeller hub, a centrifugal governor directly connected to and controlling the propeller blades, resilient mechanism extending between the weighted governor arms to regulate and counteract the centrifugal force of the governor weights.

4. The combination of a propeller shaft, a hub affixed to it, a propeller blade, a governor attached to the propeller blade, an

elastic member operatively attached to the governor and operating to counteract the 20 centrifugal force of the governor weight.

5. In a device of the class described as a new article of manufacture, a governor device comprising a weight, an arm to which the weight is attached, a band adjustably 25 engaged by the opposite end of the arm, the band having means operatively connecting it with a similar governor device.

6. As a new article of manufacture in a device of the class described, a governor device comprising a weight, an arm, a band to which the arm is engaged, and means on 30 the governor band operatively connecting it with a corresponding governor element, substantially as set forth.

THOMAS B. SLATE.
